TABLE LAMP BASE

William Johnston, Lombard, and Herman Gittleson and
Jules J. Gittleson, Chicago, Ill., assignors to Decor
Glo Industries, Inc., Chicago, Ill.

Filed Feb. 16, 1961, Ser. No. 63,960

Term of patent 14 years

(Cl. D48—20)

FIG. 1 is an elevational view of a table lamp base embodying our new design;

FIG. 2 is a top plan view of the same; and

FIG. 3 is a bottom plan view of the same.

The essential features of our design reside in the portion shown in solid lines.

We claim:

The ornamental design for a table lamp base, substantially as shown and described.
